DENTAL UNIT

Robert V. Turner, 8737 Nada, Downey, Calif.

Filed Mar. 25, 1963, Ser. No. 74,104

Term of patent 14 years

(Cl. D24—1)

I claim:

The ornamental design for a dental unit, substantially as shown.
